UNITED STATES PATENT OFFICE.

ROBERT H. FENN, OF WHITESTONE, NEW YORK.

AUTOMATIC LABEL FEEDER.

Original application filed December 26, 1918, Serial No. 268,296. Divided and this application filed October 7, 1920. Serial No. 415,369. Renewed July 13, 1923.

To all whom it may concern:

Be it known that I, ROBERT H. FENN, citizen of the United States, and resident of Whitestone, in the county of Queens and 5 State of New York, have invented certain new and useful Improvements in Automatic Label Feeders, of which the following is a specification.

This application is a division of my co-pending application for patent on automatic box machines, Serial No. 268,296, filed Dec. 26, 1918.

This invention relates to a mechanism for feeding paper box labels, and is illustrated 15 and described in connection with the above mentioned application for patent on automatic box machines.

The object of this invention is to provide a device for feeding paper box labels, one 20 at a time, from a stack of labels, to a receiving and conveying carriage; said carriage also to be provided with means for incidentally gumming said labels.

The invention is illustrated in the accompanying drawings, and described in the following specification.

In the drawings:—

Fig. 1 is a front elevation, in part section, of the label feeder, conveying carriage and 30 die.

Fig. 2 is a side elevation, in part section, of the label feeder, conveying carriage and die.

Fig. 3 is a front elevation of the label 35 feeder, in part section, with the feeder platen in top position.

Fig. 4 is a plan view of the label feeder showing labels N on the platen.

Fig. 5 is a sectional view of the label 40 feeder on the line A A of Fig. 1.

Fig. 6 is a sectional view of the label feeder on the line A A of Fig. 3.

Fig. 7 is a sectional view of the label 45 feeder on the line B B of Fig. 1.

Fig. 8 is a sectional view of the label feeder on the line B B of Fig. 3.

Fig. 9 is a part view of the label feeder showing the top label of a stack of labels bulged upwardly.

Fig. 10 is a part view of the label feeder showing the cam for the separator levers.

Fig. 11 is a view of the lower part of the label feeder showing the ratchet pawl just engaging the ratchet wheel.

Fig. 12 is a view showing the cam and 55 the lever means for vertically reciprocating the feeder.

A description of the mechanism and its operation follows.

At E, Figures 1, 2, and 3 is shown a carriage with its marginal die E¹ and the suction plunger E². It slides on the two horizontal rods E³ carried on the frame of the machine. It is operated reciprocally by a cam mechanism not shown. 60

The die E¹ has a hollow centre, and the suction plunger E², with its head E^{2a}, reciprocates through the die E¹. The operating mechanism for E² is not shown. The die E¹ is removably fastened to the bottom 65 of the carriage by means of the two pins E^{2b}, Figures 1 and 3.

The die E¹ has a hollow centre, and the suction plunger E², with its head E^{2a}, reciprocates vertically. At the 70 lower end it is provided with a hollow head E^{2a} communicating with the tube E^{2b}. The head is provided with a face E^{2c} shown in Fig. 1, through which small holes, larger at their inner end, are drilled, making a 75 suction plate. The suction plunger head approximates the shape of the opening through the marginal die but is smaller to provide working clearance, so that the suction plunger head can reciprocate vertically 80 through the marginal die.

The box label feeder J (J is used to denote the entire label feeding mechanism as shown in various views, positions, sections, etc., in Figs. 1 to 12 inclusive) consists of 85 a yoke platen J¹ from the lower arm of which the barrel J² depends. The barrel J² is supported and guided in the bearing J³, which is separate from the frame B⁴ of the machine, and is adjustable laterally, and 90 held to a setting by the bolts J⁴. The lower end of the barrel J² is closed by the washer J⁵, against the bottom of which, the barrel roller J⁶ presses. 95

The roller J⁶ is rotatably mounted on the 100 end of the lever J⁷ which is carried on the shaft J⁸ which has bearings in the frame B⁴.

The cam J^9 Fig. 12, through its cam lever, cam roller, cam washer and cam rod J^{10} which screws into the rod end J^{11} , pivotally connected to the lever J^7 , reciprocates the 5 barrel J^2 and yoke platen J^1 and attached parts in accordance with the cam outline.

Projecting upwardly from the yoke platen J^1 , Fig. 1, are the two side arms J^{13} which are guided by the guide arms J^{14} , and 10 the two end arms J^{15} , which are guided by the two guide arms J^{16} . Also projecting vertically upwards from the yoke or platen J^1 are the four label guides J^{17} , which engage the labels N as shown in Fig. 4.

15 Slidably mounted on the four label guides J^{17} , are the screw platen J^{18} and the box label platen J^{19} . Pinned into the screw platen J^{18} is the feed screw J^{20} , threaded from end to end. Between the arms of the 20 yoke platen J^1 , and threaded on the screw J^{20} is the ratchet J^{21} , which has a bearing on the top of the barrel J^2 .

The underside of the ratchet wheel J^{21} is 25 provided with teeth J^{22} . The pawl J^{23} is pivotally mounted on the bearing J^3 at J^{24} . It has a lower arm J^{25} to which the spring J^{26} , fastened at J^{27} , is attached. Projecting from the pawl J^{24} there is also a lug J^{28} which, as the spring pulls the arm 30 J^{25} , rotates the pawl until the lug strikes the stop spring J^{29} as shown in Fig. 11 which also shows the yoke platen J^1 descending, and the pawl J^2 about to strike one of the teeth J^{22} . As the yoke descends 35 the ratchet wheel tooth J^{22} engages the pawl, and the ratchet wheel is rotated to the left, the space of one tooth. Fig. 1 shows the yoke platen J^1 at the bottom of its stroke.

40 The compression springs J^{30} , one around each label guide J^{17} , and resting on the screw platen J^{18} , support the label platen J^{19} resiliently, so that any labels placed on the label platen, reciprocate as a whole 45 with the yoke platen J^1 and also move upwardly, relatively to the yoke platen J^1 , as the ratchet wheel is rotated to the left. The teeth J^{22} on the ratchet wheel and the 50 number of threads on the screw are arranged so that for each reciprocation of the yoke platen J^1 the label platen moves upwardly, relatively to the yoke, a distance a little greater than the thickness of the thickest label used. A slot in the label 55 platen J^{31} slidably engages the rib J^{32} on the arm J^{15} and steadies and prevents rotation of the label platen about its vertical axis relative to the guide arms J^{15} and J^{13} .

To prevent the ratchet wheel from rotating backwards as the yoke J^1 lifts away 60 from the pawl J^{23} , the check pawl J^{33} , pivotally supported and held in operating position by the leaf spring J^{34} which is mounted at J^{35} , so that it can be swung to 65 one side, allowing the check pawl J^{33} to

drop away from the ratchet wheel teeth J^{22} . This is necessary when the screw platen J^{18} , having reached its highest position, is lowered by turning the ratchet wheel to the right after pulling the pawl J^{23} down out of contact with the ratchet wheel teeth. 70

Pivotally mounted on each end arm J^{13} are the separator levers J^{36} . Each is constructed and operated as follows:—The 75 spring J^{37} keeps the lever J^{36} always pulled toward the arm J^{15} so that the lower end J^{38} always rides against the guide arm J^{16} . The separator lever J^{36} is carried in the slot J^{41} Fig. 4 and is fastened to the pin J^{40} 80 which is rotatably and slidably mounted in the portion of the arm at each side of the slot J^{41} . Between the head of the said pin J^{40} and the side of the arm J^{15} is the expanding spring J^{42} which tends to keep the 85 whole separator lever J^{36} pulled over against the left side of the slot J^{41} . But on the side of each lever J^{36} , just below the slots J^{41} , are the small cams J^{43} Fig. 1, which are 90 shown engaged by the pins J^{44} which are fastened in the guide arms J^{16} . In this position the lower part of the separator lever J^{36} has been pushed to the right, until it dropped into the lower end of the cam groove J^{45} Fig. 10. In Fig. 2, J^{38} is shown 95 just ready to drop into the cam groove as soon as the label feeder rises. When it does rise, J^{38} slides down into the cam groove and the upper end of the lever J^{36} which carries a spring supported rubber pusher J^{46} , moves 100 inwardly and downwardly, as shown in Fig. 9, until, both levers acting, the pushers strike the top label of a stack carried on the label platen, and push each end of the top label toward the centre which bellies it up 105 as shown. This separates the top label from those beneath and leaves a film of air between.

As the feeder continues to rise the part 110 J^{38} slides upwardly and out of the cam groove J^{45} , reaching the straight surface J^{47} , and the pushers rise and move outwardly. As soon as J^{38} is out of the cam groove, the cam J^{43} having also moved upwardly and out of engagement with the pin 115 J^{44} , the spring J^{42} pulls the separator lever J^{36} to the left so that when the feeder descends, the lower portion J^{38} of the lever J^{36} rides on the wall J^{48} , therefore the pushers J^{46} do not move inwardly as the feeder 120 descends. As it descends however, the cam lug J^{43} as before explained, again contacts with the pin J^{44} and the separator lever J^{36} is again moved to the right and J^{38} is 125 again ready to drop into the cam groove J^{45} on the next upward stroke.

Pivotally mounted on the side arms J^{13} are the parting levers J^{49} Fig. 1 (there are two but may be more and one is similar to the other) shown in contact with the adjust- 130

ing screws J^{51} , and held in contact by the leaf springs J^{50} . To the upper end of the lever J^{49} is attached the thin parting spring J^{52} .

- 5 The adjusting screws are so set, that just at the instant the label pushers have bellied up the label, the lower portion of the parting lever J^{49} , also moving upward slides over the adjusting screw J^{51} allowing the 10 parting spring J^{52} to move inwardly and between the top label, which has been bellied up, and the stack of labels below, as shown in Fig. 3. It remains in this position until the feeder descends and the lever J^{49} again 15 striking the adjusting screw J^{51} , moves inwardly, while the parting spring J^{52} moves outwardly ready for the next upward stroke. The function of the parting springs is to prevent any of the lower labels from being 20 extracted from the feeder when the topmost label is being withdrawn.

Each upper end of the guide arms J^{17} is slotted and a flat label holder J^{53} is pivotally mounted in the slot so that it presents 25 a narrow edge toward the label and is held pressed toward them by the leaf spring J^{54} . The upper part of J^{53} is bevelled upwardly and outwardly and the lower portion downwardly and inwardly. The upper portion 30 is so made as to provide clearance for the marginal die E^1 when the feeder is at the top of its stroke as in Fig. 3. The lower portion is so made that the labels which fit loosely between the guide arms J^{17} when 35 being pushed upwardly by the label platen will centre themselves exactly, and also be held below the points J^{55} , above which point the labels are never fed, so that they do not fly off when the feeder reciprocates.

40 Pivoted on the label platen J^{19} , Fig. 1, is the pressure link J^{56} , whose foot J^{57} slidably fits into a slot J^{58} in the screw platen J^{18} . When the feeder rises with a 45 stack of labels as in Fig. 3 and the labels come in contact with the marginal die E^1 , the springs J^{30} compress and the foot of the pressure link J^{57} slides to the left in the slot J^{58} .

Referring to Fig. 5 the foot J^{58} is shown 50 in starting position, in contact with the arm J^{59} of the upper collar J^{60} , the spring J^{61} acting through the arm J^{62} maintaining the arm J^{59} always in contact with the foot J^{58} . The upper collar J^{60} is mounted and pinned 55 fast to the vertical square rod J^{63} which extends downwardly from the label platen, through the screw platen and through a bearing J^{64} in the barrel bearing J^3 . Just above the bearing J^{64} and resting on it and 60 held down by the clip J^{65} is the lower collar J^{66} provided with a square hole, approximately the same size as the square rod J^{63} which slidably passes through it. Therefore when the upper collar J^{60} rotates to the 65 left as the link J^{57} pushes it, when the

springs J^{30} are compressed, as the feeder rises to the top of its stroke, the rod J^{63} also rotates the lower collar J^{66} to the left. On the lower collar J^{66} is an arm J^{67} Figs. 7 and 8 against which the lower arm of the pawl J^{23} is held in contact by the spring J^{26} .

Figs. 7 and 11 show the position of J^{67} and the pawl J^{23} before the feeder rises. Figs. 8 and 3 show their positions when the feeder has reached the top of its stroke and the springs J^{30} have been compressed. The arm J^{67} has pushed the lower arm J^{25} , of the pawl J^{23} , to the right, and the pawl J^{23} is thereby swung downwardly to the left. The leaf spring J^{68} , made so as to be adjustable up or down by means of the slot J^{69} and provided with the nose J^{70} , is shown in Fig. 3 in position so that the nose J^{70} is in contact with, and under, the lug J^{28} of the pawl J^{23} , thereby holding the pawl J^{23} down so that when the feeder descends the pawl will not come in contact with the teeth J^{22} of the ratchet wheel J^{21} . The ratchet wheel therefore will not be rotated, and the screw and the label platen will not be fed upwardly.

In order to release the spring J^{68} the release pin J^{71} Fig. 3 is provided. When the feeder descends, this release pin strikes the upper part of the spring J^{68} and pushes it away from the pawl lug J^{28} as shown in Fig. 17. The pawl, released, is immediately pulled to normal position by the spring J^{26} , the label platen having in the mean time raised, as the springs J^{30} again expanded, allowing the square rod J^{63} to rotate back to its normal position.

In operation, the stroke of the feeder is so arranged, that with the labels on the label platen, and the feeder J at the top of its stroke, the pressure of the labels against the marginal die E^1 is sufficient to compress the springs J^{30} just enough so that the pawl J^{23} , actuated by the square rod J^{63} , and attached parts as above described, is depressed 105 similar to the position shown in Fig. 3 but just a little higher so that the nose J^{70} of the leaf spring J^{68} does not catch under the lug J^{28} .

This is the normal condition when the labels are just at the right height. But, since at each upward stroke of the feeder, a label is removed from the top of the pile of labels, and for each stroke of the feeder the pile is fed upwardly a distance greater than the thickness of the label, it is evident, that after a number of strokes the labels would be too high and some would fall from between the guide arms J^{17} . However this cannot happen because as soon as the labels 120 are fed up a little higher than normal position, the springs J^{30} are compressed a little more than normal and consequently, the pawl J^{23} , through the mechanism intervening between the label platen and itself, 125 130

is depressed until the nose J^{70} does catch under the lug J^{28} of the pawl and holds it depressed so that when the feeder descends, the pawl, not engaging the ratchet wheel 5 teeth, the screw and label platens are fed no higher for that stroke. By the above means the labels are always maintained at the correct operative height and the pressure requisite for the attainment of the 10 print of the adhesive from the marginal die is maintained practically a constant.

An adjustment is also provided to rotate the feeder slightly about its vertical axis so as to slightly change the position of the label 15 N relatively to the marginal die E^1 . The object of this is to change the position of the label on the feed slide, since the carriage and suction plunger maintain the labels in the same position at it occupied in the feed- 20 er, when it deposits it on the feed slide, in order to make the sides of the label parallel with the sides of the box blank folded around the expansible plunger. This is accom- 25 plished by the bar J^{72} Figs. 4 and 9 held in place by the screws J^{73} . Depending from this bar is the rod J^{74} over which the slot J^{75} in the arm J^{13} slides. The feeder is rotated by moving the bar J^{72} as required, forward or back.

30 In operation the die E^1 having been coated with an adhesive, is moved directly over the feeder J . The feeder has, in the meantime, been rising. The top label is separated from the lower ones, and as the feeder reaches the 35 top of its stroke, the top label is pressed against the under side of the marginal die E^1 . Then the suction plunger E^2 descends and the plunger head E^{29} rests upon the top label and continues down in contact with 40 it as the feeder descends. Just as the plunger head E^{29} contacts with the top label, appropriate means, not shown, opens an air suction acting through the holes in the face of the plunger E^{30} , and sucks the label tightly 45 against it. Therefore when the suction plunger stops its descent, a short distance above the table B^1 , the top label is held fast to it, while the feeder, with the balance of the labels, descends to the bottom of its 50 stroke.

It is obvious that the action of the suction plunger head would be the same whether the die E^1 is coated with adhesive or not. That is, the feeder will feed the labels to the suction plunger whether they are marginally coated with adhesive or not.

What I claim is:-

1. In an automatic box machine, a label feeder comprising a vertically reciprocated yoke platen with cam means for operating the same, said yoke platen provided with a hollow shaft extending below, and a bearing therefor; vertical arms extending upwardly from the sides of said yoke platen, and guides, external of said feeder, therefor, 60 and guides therefor.

2. In an automatic box machine, a label feeder comprising a vertically reciprocated yoke platen with cam means for operating the same, said yoke platen provided with a hollow shaft extending below, and a bearing 70 therefor; vertical arms extending upwardly from the sides of said yoke platen, and guides, external of said feeder, therefor, together with label guides extending vertically upwards from said yoke platen. 75

3. In an automatic box machine, a label feeder comprising a vertically reciprocated yoke platen with cam means for operating the same, said yoke platen provided with a hollow shaft extending below, and a bearing 80 therefor; vertical arms extending upwardly from the sides of said yoke platen, and guides, external of said feeder, therefor; together with a screw platen provided with a screw extending downwardly through said 85 yoke platen and into said hollow shaft, a ratchet wheel between said yoke platen and said hollow shaft, threaded to fit said screw, carried on same, having a bearing on the top of said hollow shaft and operated by 90 a pawl pivoted on said hollow shaft bearing.

4. In an automatic box machine, a label feeder comprising a vertically reciprocated yoke platen with cam means for operating the same, said yoke platen provided with a 95 hollow shaft extending below, and a bearing therefor; vertical arms extending upwardly from the sides of said yoke platen, and guides, external of said feeder, therefor; a screw platen provided with a downwardly extending screw passing through said yoke platen into said hollow shaft, a ratchet wheel between said yoke platen and said hollow shaft, threaded to fit said screw, carried on same and having a bearing on 100 the top of said hollow shaft and operated by a pawl pivoted on said hollow shaft bearing, together with label guides extending vertically upward from said yoke platen and 105 passing through clearance holes in said screw platen. 110

5. In an automatic box machine, a label feeder comprising a vertically reciprocated yoke platen with cam means for operating the same, said yoke platen provided with a 115 hollow shaft extending below, and a bearing therefor; vertical arms extending upwardly from the sides of said yoke platen, and guides, external of said feeder, therefor; a screw platen provided with a downwardly extending screw passing through said yoke platen into said hollow shaft, a ratchet wheel between said yoke platen and said hollow shaft, threaded to fit said screw, carried on same, and having a bearing on top 120 of said hollow shaft and operated by a pawl pivoted on said hollow shaft bearing, together with label guides extending vertically upward from said yoke platen and 125 passing through clearance holes in said 130 screw platen.

- 5 screw platen; an upper label platen, slidably mounted on said label guides, with springs resting on said screw platen and resiliently supporting said label platen.
6. In an automatic box machine, a label feeder comprising a vertically reciprocated yoke platen with cam means for operating the same, said yoke platen provided with a hollow shaft extending below, and a bearing therefor; vertical arms extending upwardly from the sides of said yoke platen, and guides, external of said feeder, therefor; a screw platen provided with a downwardly extending screw passing through said yoke platen into said hollow shaft, a ratchet wheel between said yoke platen and said hollow shaft, threaded to fit said screw, carried on same and having a bearing on top of said hollow shaft, with means to operate said ratchet wheel, together with label guides extending vertically upwardly from said yoke platen and passing through clearance holes in said screw platen; an upper label platen, slidably mounted on said label guides, with springs resting on said screw platen and resiliently supporting said label platen together with means in said label platen for slidably engaging a plurality of said vertical arms.
7. In an automatic box machine, a label feeder comprising a vertically reciprocated yoke platen, with cam means for operating the same, provided with a hollow shaft extending below from a yoke, and a bearing therefor; vertical arms extending upwardly from the sides of said yoke platen and guides therefor; a screw platen provided with a screw adapted to extend downwardly, through said platen, into said hollow shaft; a ratchet wheel between said yoke platen and said hollow shaft threaded to fit said screw, carried on same, and having a bearing on top of said yoke hollow shaft; label guides extending upwardly from said yoke platen and passing through clearance holes in said screw platen; an upper label platen slidably mounted on said label guides and provided with slotted lugs slidably engaging a plurality of said vertical arms; springs resting on said screw platen and resiliently supporting said label platen; a link, pivotally mounted on said label platen, adapted to slide in a groove in said screw platen; a rod passing vertically through said label platen, screw platen, yoke platen and a bracket extending from the bearing of said hollow shaft; a lever fastened near the upper end of said rod, resting on said screw platen and held in contact with said link by spring means; a pawl lever slidably mounted on and engaging said rod, and mounted in a bearing on said bracket so that motion communicated to said link, causes said rod to rotate about its vertical axis, transmitting its motion to said pawl lever; a pawl adapt-
- ed to engage the teeth of said ratchet wheel, and pivotally mounted on said hollow shaft bearing; an arm attached to the hub of said pawl maintained in contact with said pawl lever by spring means; a stop to engage a lug on said pawl; a leaf spring adapted to engage said pawl and a pin extending downwardly from said yoke platen adapted to release said leaf spring from engagement with said pawl lug when said yoke platen descends; a stop pawl, carried on the side of said yoke platen, spring actuated and positioned, adapted to maintain said ratchet wheel from turning when said yoke platen rises, and means to release said stop pawl from contact with said ratchet.
8. In an automatic box machine, a label feeder comprising a vertically reciprocated yoke platen, with cam means for operating the same, an intermediate platen carried by said yoke platen, an upper platen resiliently supported from said intermediate platen; arms extending vertically from said yoke platen engaged by lugs on said upper platen, with guides for said arms; label guides extending vertically from said yoke platen through clearance holes in said upper platen; spring actuated means pivotally supported on said yoke platen arms and operated by contact with cam means, carried by said yoke platen arm guides, to separate the top label from a stack carried on said upper platen, as said yoke platen rises; pin and cam means to restore said separating means to its initial operating position (when said label platen descends).
9. In an automatic box machine, a label feeder comprising a vertically reciprocated yoke platen with cam means for operating the same, an intermediate platen, carried by said yoke platen, an upper platen resiliently supported from said intermediate platen; arms extending vertically from said yoke platen engaged by lugs on said upper platen, with guides for said arms; label guides extending vertically from said yoke platen through clearance holes in said upper platen; spring actuated means, pivotally supported on said yoke platen arms and operated by contact with cam means, carried by said yoke platen arm guides, to separate the top label from a stack carried on said upper platen, as said yoke platen rises; pin and cam means to restore said separating means to its initial operating position (when said yoke platen descends) together with spring actuated means pivotally mounted on said yoke platen arms, operated by contact with an adjustable screw, adapted to intervene between said top label and those beneath, and to retain the lower labels in position, as said top label is removed.
10. In an automatic box machine, a label feeder comprising a vertically reciprocated

yoke platen with cam means for operating the same, an intermediate platen, an upper platen resiliently supported from said intermediate platen; label guides extending, vertically from said yoke platen, through clearance holes in said upper platen together with label retainers, pivotally mounted in slots in the upper portion of said label guides, and adapted to be held in contact with a stack of labels on said upper platen by spring means carried on said label guides, substantially as described.

11. In an automatic box machine, a label feeder comprising a vertically reciprocated platen, an intermediate platen, carried by, and automatically adjustable, vertically, in relation to said platen; a label platen resiliently supported from said intermediate platen; label guides adapted to position and maintain a stack of labels on said label platen; label holders pivotally mounted and spring positioned in slots in the upper ends of said label guides; together with means to present a stop to contact against said stack of labels, as it approaches its highest position, to cause pressure between said labels and said stop and to cause said label platen to move relatively toward said intermediate platen.

12. In an automatic box machine, a label feeder comprising a vertically reciprocated yoke platen, an intermediate platen, carried by, and automatically adjustable, vertically, in relation to said yoke platen; a label platen resiliently supported from said intermediate platen; label guides adapted to position and maintain a stack of labels on said label platen; means to present a stop to contact against said stack of labels, as it approaches its highest position, to cause pressure between said labels and said stop and to cause said label platen to move, relatively, toward said intermediate platen together with a suction head operating through said stop adapted to hold the top label, of said stack of labels, to itself by suction as said yoke platen moves downwardly.

13. In an automatic box machine, a label feeder comprising a vertically reciprocated yoke platen, an intermediate platen, carried by, and automatically adjustable, vertically, in relation to said yoke platen; a label platen resiliently supported from said intermediate platen; label guides adapted to position and maintain a stack of labels on said label platen; means to present a stop to contact against said stack of labels, as it approaches its highest position, to cause pressure between said labels and said stop and to cause said label platen to move, relatively, toward said intermediate platen; a suction head operating through said stop adapted to hold the top label, of said stack of labels, to itself by suction as said yoke

platens moves downwardly, together with means to move said suction head and said stop to convey said label and deposit it on a receiving means.

14. In an automatic box machine, a label feeder comprising a vertically reciprocated yoke platen, an intermediate platen, carried by, and automatically adjustable, vertically, in relation to said yoke platen; a label platen resiliently supported from said intermediate platen; label guides adapted to position and maintain a stack of labels on said label platen together with means to present a stop to contact against said stack of labels, as it approaches its highest position, to cause pressure between said labels and said stop and to cause said label platen to move, relatively, toward said intermediate platen together with means actuated by the reciprocation of said yoke platen, adapted to automatically readjust the intermediate platen relatively to the yoke platen during each reciprocation of said yoke platen.

15. In an automatic box machine, a label feeder comprising a vertically reciprocated yoke platen, an intermediate platen, carried by, and automatically adjustable, vertically, in relation to said yoke platen; a label platen resiliently supported from said intermediate platen; label guides adapted to position and maintain a stack of labels on said label platen; means to present a stop to contact against said stack of labels, as it approaches its highest position, to cause pressure between said labels and said stop and to cause said label platen to move, relatively, toward said intermediate platen; means actuated by the reciprocation of said yoke platen, adapted to automatically readjust the intermediate platen, relatively to the yoke platen, during each reciprocation of said yoke platen together with means actuated by the relative movement of said label platen to said intermediate platen to prevent said readjustment of said intermediate platen to said yoke platen.

16. In an automatic box machine, a label feeder comprising a vertically reciprocated yoke platen, an intermediate platen, carried by, and automatically adjustable, vertically, in relation to said yoke platen; a label platen resiliently supported from said intermediate platen; label guides adapted to position and maintain a stack of labels on said label platen, said label guides provided with means to hold said labels on said label platen while it moves relatively to said intermediate platen and reciprocates with said yoke platen, and to prevent more than the top label from being removed from said stack of labels.

17. In an automatic box machine, a label feeder comprising a vertically reciprocated
